UNITED STATES PATENT OFFICE.

WILFRED T. BIRDSALL, OF MONTCLAIR, NEW JERSEY, ASSIGNOR, BY MESNE ASSIGNMENTS, TO WESTINGHOUSE ELECTRIC & MANUFACTURING COMPANY, A CORPORATION OF PENNSYLVANIA.

METHOD OF EXHAUSTING.

1,318,832.

Specification of Letters Patent. Patented Oct. 14, 1919.

Application filed May 4, 1915. Serial No. 25,864.

To all whom it may concern:

Be it known that I, WILFRED T. BIRDSALL, a citizen of the United States, and a resident of Montclair, in the county of Essex and State of New Jersey, have invented a new and useful Improvement in Methods of Exhausting, of which the following is a specification.

My invention relates to the manufacture 10 of vapor electric apparatus having a highly-exhausted container of vitreous material, such, for example, as a glass rectifier, and it has for its object to provide a simple, economical and effective method of removing deleterious gases from the interior of 15 the container during the exhausting process.

The single figure of the accompanying drawing is a side view, partially in section and partially in elevation, of a vapor arc 20 rectifier, together with attendant apparatus necessary for carrying out my invention.

It is well known that in the manufacture 25 of vapor rectifiers and other like apparatus requiring a high operating vacuum, extreme difficulty is encountered in removing occluded gases from the inner surfaces of the container walls. While, at the conclusion 30 of the pumping process, the device may indicate an extremely high vacuum, yet when the rectifier is put into operation and the walls are highly heated, it is found that occluded gases are given off which tend to lower the vacuum to such a marked degree as to seriously impair the rectifier operation. In order to remove the gases, it has been customary in the past to highly heat 35 the container wall during the process of exhausting as, for example, by baking it in an oven or by passing current through the device while the pump is still connected thereto. The oven treatment is not entirely satisfactory for, no matter how highly the oven may be heated, it is found that actual 40 operation will set free occluded gases even though heat, by itself, fails to do so. On the other hand, in the ordinary rectifier, if sufficient heat is generated by the passage of current between the electrodes to satisfactorily drive off all the occluded gases, it is 45 found that such an amount of current is required as to seriously impair the seals.

I have found that, by surrounding a rectifier with a medium having less heat-absorbing capacity than that in which it is

intended to operate and by then passing 55 current through the device, the walls may be so highly heated as to effectually remove the occluded gases and, at the same time, such a small amount of current is necessary for the required heat that the seals are not affected. 60 I find that, by operating a rectifier in the air which is to be normally operated in a liquid such, for example, as water or oil, I am able to secure a vacuum of great permanence. 65

Referring to the accompanying drawings, a glass rectifier bulb of conventional type is shown at 1 and embodies a pair of main anodes 2 and 3, a main cathode 4 and an auxiliary starting and maintaining anode 5. 70 Connection to a pump may be made by a suitable tubulation 6. The rectifier may be started and maintained in operation by a small arc between the anode 5 and the cathode 4, current being derived from any suitable direct current source, such, for example, as a battery 7. Load current for the main anodes 2 and 3 is derived from a transformer 8 and may be adjusted in voltage by suitable taps 9 and 10, and may be 75 adjusted in amount by a suitable rheostat 11. The rectifier 1 is designed to be operated in a cooling fluid, as, for example, by immersion in a tank 12. On account of the much higher heat absorption of a liquid 80 than of the atmosphere, the container 1 would be heated to collapse were it attempted to run full-load current therethrough in the atmosphere. In the process of manufacture, however, I first exhaust the 85 tube 1 in the ordinary manner and then pass current thereto from the source 8 in such amounts as to heat the container to a very high degree. The amount of current necessary for this operation is small, owing 90 to the low heat radiation, and I am enabled to obtain a very high heating of the container wall without using undue amounts of energy and without endangering the seals. At the same time, abnormally favorable 95 electrostatic conditions are provided within the container 1 for the liberation of occluded gases.

With the above described process, the gas may be effectively removed from the container walls, but the abnormally high vapor pressure caused by the small heat-radiating capacity produces a "stringing" of the arc 105

and the heating of the anodes only in small sharply defined spots. The next step in the complete exhausting process is, in effect, the converse of that above described. In order 5 to heat the entire anodes thoroughly, it is necessary to provide an abnormally high vacuum and this result may be obtained by surrounding the rectifier with a medium of greater heat-absorbing capacity than that 10 employed in normal operation. If the rectifier is designed to be submerged in the liquid of the tank 12, when, under normal load, the desired abnormal cooling may be provided by immersing a cooling coil 14 in said liquid 15 and by circulating brine or a similar fluid therethrough. The vapor pressures within the rectifier will then be reduced to an abnormally low amount, so that substantially all the current flow within the container 20 takes place by current carriers originating at one terminal and passing to the other so that a great share of the energy represented by the voltage drop within the device is delivered at the anodes, heating all portions 25 thereof to a higher degree than would be the case in normal operation and effectively driving off the occluded gases therefrom. After the exhausting process has been completed, the entire device may be left in the 30 liquid of the tank 12 for normal operation and it will there, at rated load current, never be subjected to as severe treatment as that just described. The vacuum will therefore be substantially unaffected by liberation of 35 occluded gases during normal operation.

I may provide the conducting leads to the different electrodes with heavy insulating coatings 13-15, as shown, in order to prevent short circuiting of the device and harmful 40 electrolytic action if an operating cooling medium of conducting material, such for example, as water, be employed.

I have described my invention as applied to the air treatment of a bulb which is to 45 operate under water, but I desire to have it construed broadly to cover any method whereby a rectifier bulb is treated out during the exhausting process in mediums having lower and higher heat absorbing capacities 50 than that in which the bulb is designed to operate.

While I have described my invention in its preferred form, it will be obvious to those

skilled in the art that it is susceptible of various minor changes and modifications 55 without departing from the spirit thereof, and I desire, therefore, that no limitations shall be placed thereupon except such as are imposed by the prior art or are specifically set forth in the appended claims. 60

I claim as my invention:

1. The method of liberating occluded gases from the interior of a partially exhausted vacuum-type electric device by means of heating current transmitted thereto through the working seals thereof which comprises surrounding said device by a less effective heat-absorbing medium than that in which it is designed to operate, passing current therethrough of substantially the 70 same magnitude as the normal working current, and pumping out the liberated gases.

2. The method of providing abnormal gas-liberating conditions within the container of a vacuum-type electric device by 75 means of heating current passing through the working-current path thereof, without overloading the seals thereof, which comprises operating said device in a medium having less heat-absorbing power than that 80 in which the device is designed to normally operate and passing substantially normal load current therethrough.

3. The method of heating a vacuum-type electric device to a gas-freeing degree by heat 85 electrically generated therein without unduly heating the leading-in conductors thereof, which comprises immersing said device in a poorer heat-absorbing medium than that in which it is designed to normally operate 90 and passing substantially load current therethrough.

4. The method of removing occluded gases from the electrodes of a vapor electric device which comprises operating said device in 95 a medium having greater heat-absorbing power than that in which it is designed to normally operate, whereby the vapor pressure will be abnormally lowered and all portions of the anodes will be highly heated. 100

In testimony whereof I have hereunto subscribed my name this 28th day of April, 1915.

WILFRED T. BIRDSALL.
